CLAIM

The ornamental design for a wipes dispenser, as shown and described.

DESCRIPTION

FIG. 1 is a top, front, right perspective view of a dispenser embodying our new design.

FIG. 2 is a front elevational view of the dispenser shown in FIG. 1.

FIG. 3 is a right side elevational view of the dispenser shown in FIG. 1, the left side elevational view being a mirror image thereof.

FIG. 4 is a rear elevational view of the dispenser shown in FIG. 1. and,

FIG. 5 is a top plan view of the dispenser shown in FIG. 1. The large-dash small-dash broken lines in the drawings near an upper portion of the dispenser and near a latch on a front portion of the dispenser represent the bounds of the claimed design while all other broken lines in the drawings represent unclaimed environmental subject matter and form no part of the claim.
